Dec 1081

Hiram Bissell of Hartford, Conn.
Letters Patent No 1081, Dated Feb 15, 1859.

The Schedule referred to in the Letters Patent and making part of the same.

To all whom it may concern:

Be it known that I, Hiram Bissell, of Hartford County of Hartford and State of Connecticut, have invented or produced a new and original design for Hot Air Furnaces and I do hereby declare that the following is a full and exact description of the same:

Having reference to the accompanying drawings and letters of reference.

In the accompanying drawings

Figure 1. Represents an isometrical elevation, showing the shape and configuration of its several parts.

A. is the lower part of the fire pot, (detached from the ash box) gradually increasing its dimensions upward, B. is the upper portion of the fire pot, joining the lower portion A. at H. expanding upward, and outward, from a round shape at the line H, to a square form at the line I. C. is a projecting, feeding aperture, the upper part receding, D. is the fire chamber and radiator resting upon the bed piece over the fire pot B, and tapering upward into smaller dimensions, presenting large radiating surface.

E. are the radiators placed one over the other horizontally to the height of the fire chamber D.

The radiator E' surmounts and connects the fire chamber D, and the radiators E. at J. J' the back end thereof diminishing in width, and increasing in depth at K. a flange to receive the smoke pipe, F. are supports for the radiators.

What I claim therefore and desire to secure by Letters Patent is.

The shape and configuration of the said furnace as herein described and shown in the drawings.

Witnesses.

O. F. Summer.

Jeremy W. Blif.
